TRAVELER

William Wesley Bassett, Pawtucket, R. I., assignee
or to A. B. Carter, Incorporated, Gastonia, N. C.,
a corporation of North Carolina

Application April 10, 1937, Serial No. 136,100

4 Claims. (Cl. 118—61)

This invention relates to ring travelers for spinning machines.

Ring travelers when in operation on a spinning machine travel at a very fast rate of speed around 5 the ring and when so traveling the traveler floats or has practically no contact with the ring.

Various traveler cross-sections have been proposed and used, such for instance as round, flat and half-oval, that is oval or curved on one side 10 and flat on the other.

This invention has for its salient object to provide a traveler so designed as to cross-section as to reduce the friction of the yarn on the traveler to a minimum.

15 Another object of the invention is to provide a traveler having a cross-section so designed as to reduce to a minimum the air resistance on the traveler.

Another object of the invention is to provide 20 a traveler so designed as to cross-section as to equalize the weight, thereby producing a more perfect balance.

Further objects of the invention will appear 25 from the following specification taken in connection with the drawing which forms a part of this application and in which

Fig. 1 is a sectional elevation of a traveler ring having mounted thereon one form of traveler constructed in accordance with the invention, and 30 Fig. 2 is an enlarged transverse sectional elevation of the traveler.

In the embodiment of the invention illustrated in the drawing there is shown a traveler 10 which may be of any desired form or shape and 35 in the form illustrated has hooks 11 and 12 formed on the ends thereof for embracing the spinning ring 13. The yarn Y is shown as leading downwardly to the ring 10, passing under the angular portion 15 of the ring and being led to the bobbin 40 or spool S.

The particular novel feature of the traveler consists in the cross-section which is shown in the enlarged view in Fig. 2. From this figure it will be noted that the surfaces 20 and 21 of the 45 traveler are curved and meet at the edges 23 and 24 in lines which lie in the plane of the major axis of the cross-section.

The yarn Y approaches the traveler from an angle and engages one of the surfaces 20 or 21 substantially on a tangent and passes around this surface and leaves the surface also substantially on a tangent. Therefore there is a minimum 5 amount of frictional engagement between the yarn and the traveler. Furthermore due to the shape of the cross-section illustrated in Fig. 2 it will be evident that the air resistance to the movement of the traveler around the ring will 10 be reduced to a minimum. Moreover since the traveler is symmetrical with reference to its major axis or to the major axis of the cross-section thereof, a perfectly balanced construction is provided.

If desired, the edges of the traveler or ends of 15 the oval surfaces shown at 23 and 24 may be slightly rounded instead of sharp.

Although one specific embodiment of the invention has been particularly shown and described, it will be evident that modifications and changes in the construction may be made without departing from the spirit and scope of the invention, as expressed in the following claims.

Having thus described my invention, what I 25 claim is:

1. A ring traveler having means for embracing 30 a traveler ring, said traveler cross section having on opposite sides of the major axis thereof convex, symmetrical surfaces.

2. A ring traveler having means for embracing 35 a traveler ring, said traveler cross section having oppositely facing convex, symmetrical surfaces, said convex surfaces meeting at each longitudinal edge of the traveler in a line.

3. A ring traveler having means for embracing 40 a traveler ring, said traveler cross section having oppositely facing convex, symmetrical surfaces, said convex surfaces meeting at the edges of the traveler.

4. A ring traveler having means for embracing 45 a traveler ring, said traveler having a cross section comprising oppositely facing symmetrical, convex surfaces, said surfaces converging from the center to the edges of the traveler.

WILLIAM WESLEY BASSETT.
